W. G. BUCK

VALVE ROTATING DEVICE

Filed June 5, 1918

Inventor
Wilmer G. Buck.
By: Wm. Bond Atty.

UNITED STATES PATENT OFFICE.

WILMER G. BUCK, OF FREMONT, NEBRASKA, ASSIGNOR TO CONTINENTAL ENGINEERING CORPORATION, OF OMAHA, NEBRASKA, A CORPORATION OF NEBRASKA.

VALVE-ROTATING DEVICE.

Application filed June 5, 1918. Serial No. 238,276.

To all whom it may concern:

Be it known that I, WILMER G. BUCK, a citizen of the United States, residing at Fremont, in the county of Dodge and State of Nebraska, have invented certain new and useful Improvements in Valve-Rotating Devices, of which the following is a specification.

The present invention relates to a device employed in conjunction with puppet valves of internal combustion engines for the purpose of giving to the valve member a partial rotative movement while it is moving in one direction, the principle of operation involved being fully shown and described in Patent No. 1,183,852, granted to me May 23, 1916, and No. 1,244,287, granted to me October 23, 1917.

The objects of the invention are, to provide a portion affixed to the valve stem and a portion loose on the valve stem, but connected to said affixed portion so that both portions move with the valve stem; to provide a one-way acting clutch mechanism between the portion affixed to the valve stem and the portion loose on the stem; and to impart an oscillating rotative movement to the loose portion as it moves with the valve stem, said clutch mechanism exerting a clutching action when the loose portion is rotated in one direction, thereby rotating the affixed portion and valve stem and exerting a non-clutching action when it is rotated in the opposite direction, whereby no rotative movement is imparted to the affixed portion and valve stem.

A further object of the invention is to arrange the said clutch device in a housing located at the lower end of the valve stem, and to utilize a single locking member in the form of an ordinary valve key for connecting all of said portions in proper position with respect to the valve stem.

The invention further consists in the features of construction and combination of parts hereinafter described and claimed.

In the drawings:

Figure 1 is a section through a portion of a gas engine structure with the device of the present invention in operative position;

Figure 2 is an enlarged section through the rotating mechanism;

Figure 3 is a section on line 3—3 of Fig.

2, looking in the direction of the arrows; and

55

Figure 4 is an under face view of the rotating mechanism, showing the connection between said mechanism and the valve stem.

Referring now to the drawings, the device is illustrated in connection with a gas engine structure 5, which may be of any suitable style and character. Said structure as illustrated discloses the usual piston 6, to which is connected a piston rod 7, joined to a crank shaft (not shown). A cam shaft 8 is illustrated, having thereon cam members 9, which co-operate with tappets 10 to raise and lower the valve stems and valves in the usual manner.

The valve illustrated comprises a valve stem 11, terminating in a valve head or member 12, and is of the usual puppet type and may be employed for controlling either the inlet or exhaust openings of the engine. A bushing 13 is shown, which is formed at its upper end with a flange 14, notched as at 15; and engaging with the walls of the notch is a pin 16 fixed in the cylinder, whereby said bushing is held against rotative movement. A sleeve 17 is provided, which is formed with outwardly extending lugs or knobs 18, which travel within helical slots 19 in the bushing 13.

The sleeve 17, as will be seen from Fig. 2, terminates in a hollow head 20, and on the lower end of said head is an outwardly extending flange 21. Engaging with the flange 21 is a cap 22, which is seated or otherwise affixed to a ring 23, having therein a ball-race 24. This ball-race co-operates with a ball-race 25 in a collar 26, and the races 24 and 25 form a bearing race to receive suitable bearings 27.

The collar 26 is formed on its under face with an elongated recess 28, within which lies a pin or key 29 extending through an opening in the valve stem. In all standard valve constructions, this key and opening is present in the stem, so that the rotating device of the present invention can be applied to any form of valve without any alteration therein, the key 29 forming the sole means for securing and maintaining all of the rotating parts in proper position with respect to the stem.

Extending upward from the collar 26 is

with considerable particularity, it is not deemed to be limited other than may be by the terms of the appended claims. 65

I claim:

1. In a device of the class described, the combination of a reciprocating valve stem having a valve member thereon, a sleeve surrounding said stem and loose thereon, said sleeve terminating in a hollow head at the lower end thereof, a collar affixed to the valve stem, and having a part thereof extending within the hollow head of the sleeve, a connection between the collar and sleeve causing them to move back and forth simultaneously as the stem reciprocates, means for imparting an oscillating rotative movement to the sleeve as it moves back and forth, and a one-way acting clutch serving to impart rotative movement from the sleeve to the collar and thence to the valve stem only as the sleeve rotates in one direction, substantially as described. 75

2. In combination with a reciprocating valve stem having a valve member thereon, a member affixed to the lower end of the stem, a member loose upon the stem and positioned above the affixed member, a connection between said members causing them to move back and forth in unison with the stem, means for imparting an oscillating reciprocating movement to said loose member as it moves back and forth, said members being formed to provide a chamber at their point of juncture, and a one-way acting clutch within said chamber for imparting rotative movement from said loose member to said affixed member and thence to the valve stem only as said stem and members are moving in one direction, substantially as described. 85

3. In combination with a reciprocating valve stem having a valve member thereon, a collar affixed to the lower end of the stem, a sleeve loosely mounted on the stem above the affixed member, a connection between the collar and sleeve whereby they move back and forth in unison with the stem, means for imparting an oscillating reciprocating movement to the sleeve as it moves back and forth, a neck extending from said collar, a chambered head extending from said sleeve and arranged concentric with said neck and spaced away therefrom, a one-way acting clutch mechanism interposed between the neck and the interior of the head, whereby rotative movement is transmitted from said sleeve to said neck and thence through the collar to the valve stem only while the stem, collar and sleeve are moving in one direction, substantially as described. 105

a neck 30 (see Fig. 2), and said neck, as shown, is flattened as at 31 (see Fig. 3) on one or more sides to receive a notched disk 32. The opening through the disk is flattened in accordance with the flattening of the neck 31, and thus the disk is at all times rotatable with said neck. This disk lies within the hollow head 20 of the sleeve 17, and positioned between the face of the notches in said disk and the inner wall of the hollow head are rollers 33. 10

Assuming the tappet to be operating to force the valve upward, the collar 26, ring 23, cap 21, head 20, sleeve 17 and lugs 18 will be carried upward therewith. In fact, all portions of the rotating mechanism, with the exception of the bushing 13, will be moved in unison with the valve stem. By reason of the lugs 18 traveling in the helical slots 19, a rotative motion in the direction of the arrow (see Fig. 3) will be imparted to the sleeve 17 and head 20. This rotative motion will act to move the rollers in such manner as to cause them to wedge between the face of the teeth of the disk 32 and the inner wall of the head 20, and thus a rotative movement will be transmitted to the disk 32, and thence to the neck 30, collar 26, and through the pin 29 to the valve stem 11, which will impart a rotating motion to the valve. 25

After the tappet releases, a spring 34 will tend to move all of the rotative mechanism, except the bushing 13, together with the valve stem and valve, in a downward direction; and when moving in such direction, the sleeve 17 will be rotated in the reverse direction from that in which it was previously rotated, owing to the fact that the lugs 18 are traveling downward in the slots 19, and so on the downward movement the head 20 will be revolved in a direction reverse to that of the arrow in Fig. 3. This will tend to move the rollers 32 into the position shown in Fig. 3, wherein they will be at the deepest portion of the notch in the disk 32 and will be in a non-wedging position with respect to the face of said notches and the inner wall of the head 20. They will therefore effect no clutching engagement between the head and the disk 32, and thus on the downward movement no rotative action will be imparted to the valve stem, and it and the valve will return to seated position with a straight-line movement. 40

It is understood that although the head 20 is held in place by the cap 22, so that it is moved in unison with the movements of the valve stem, nevertheless, it has a turning movement with respect to said cap and with respect to the ring 23. 55

Although the device has been described

WILMER G. BUCK.
